UNITED STATES PATENT OFFICE.

WILLIAM ROBSON, OF TORONTO, CANADA, ASSIGNOR OF ONE-HALF TO
WILLIAM W. PIERCE, OF BUFFALO, NEW YORK.

DESIGN FOR A TRICYCLE-FRAME.

SPECIFICATION forming part of Design No. 32,407, dated March 27, 1900.

Application filed March 1, 1900. Serial No. 7,023. Term of patent 7 years.

To all whom it may concern:

Be it known that I, WILLIAM ROBSON, a subject of the Queen of Great Britain, residing at Toronto, in the Province of Ontario, Canada, have invented and produced a new and original Design for Tricycle-Frames, of which the following is a specification, reference being had to the accompanying drawing, forming part thereof.

10 This design relates to the configuration of the frame of a tricycle.

The accompanying drawing is a perspective view of a tricycle-frame embodying my design.

15 As shown in the drawing, the characteristic feature of my design consists of a longitudinal frame member A, which is substantially horizontal, a C-shaped member B, which extends rearwardly and upwardly from the rear end of said horizontal member, and an inclined front member C, which extends down-

wardly and rearwardly from the steering-head D to the front end of the horizontal portion A.

E is a fork extending downwardly and forwardly from the lower end of the steering-head.

FF' are bifurcated hangers depending from the front and rear portions of the horizontal frame member A, and G is a seat-post socket 30 arranged at the upper end of the rear member B.

What I claim is—

The design for a tricycle-frame, substantially as herein shown and described.

Witness my hand this 23d day of February, 1900. 35

WILLIAM ROBSON.
